UNITED STATES PATENT OFFICE

2,655,202

BABY TENDER

Louis Gottfried, New York, N. Y.

Application October 10, 1951, Serial No. 250,689

16 Claims. (Cl. 155—124)

1

The present invention relates to a baby tender, in general, and to an attachment forming a baby tender when combined with a juvenile table.

Baby tenders are known which could not be used for any other purpose and a separate table and chair set and a highchair had to be provided, respectively, if other uses than baby tenders were required.

It is, therefore, one object of the present invention to provide a chair with an attachment which combined with a juvenile table forms a baby tender.

It is another object of the present invention to provide a chair with an attachment which combined with a juvenile table forms a baby tender, which table has at its underface a pair of parallel disposed guide members which receive supplementary members extending from the said attachment.

It is still another object of the present invention to provide a baby tender having a chair which includes means for retaining the chair in operative position and for releasing the chair into inoperative position.

With these and other objects in view which will become apparent in the following detailed description, the present invention will be clearly understood in connection with the accompanying drawings, in which

Figure 1 is a perspective side view of one embodiment of the baby tender;

Fig. 2 is a sectional elevation along the lines 2—2 of Fig. 1;

Fig. 3 is a side elevation of the attachment with the chair secured thereto;

Fig. 4 is an end view of the baby tender;

Fig. 5 is a side elevation of the attachment with the chair, both in collapsed position;

Fig. 6 is a perspective view of another embodiment of the present invention;

Fig. 7 is a perspective bottom view of the attachment for the baby tender;

Fig. 8 is an elevational view of the same attachment;

Figs. 9 and 10 show an end view of the chair retaining means in inoperative and operative position, respectively;

Fig. 11 is a fragmentary side elevation showing a part of the chair with a second embodiment of the chair retaining means;

Fig. 12 is a cross-section along the lines 12—12 of Fig. 11;

Fig. 13 is a cross-section along the lines 13—13 of Fig. 12;

2

Fig. 14 is a bottom plan view of the same chair retaining means;

Fig. 15 is an end view of the means shown in Fig. 14; and

Fig. 16 is a fragmentary bottom perspective view showing a part of the chair with a third embodiment of the chair retaining means.

Referring now to the drawings, and in particular to Figs. 1 to 5, the first embodiment of the baby tender comprises a table 1, a chair 2 and an attachment member 3. The table 1 consists of two U-shaped members 4 forming the legs of the table 1 which support the table top 5. Preferably, horizontally disposed cross-bars 6 connect the corresponding legs of the two U-shaped members 4, and also, preferably, U-shaped channel members 7 are disposed in parallel arrangement from the front to the rear under the table 1, which channel members 7 may be supported by the cross bars 6.

The chair 2 comprises a seat 8 and a back 9, which in the present embodiment are hinged together by means of hinges 10. The seat 8 is supported by two link members 11 provided on each side of the seat 8.

The lower ends of the link members 11 are pivoted to the seat 8 and the upper ends of the link members 11 are pivoted, either permanently or releasably, to a U-shaped, preferably, tubular frame 12, the legs 13 of which are adapted to be received by the channel members 7 of the table 1. The tubular frame 12 is the main portion of the attachment member 3. Spring bolts may be disposed on the channel members 7 which engage corresponding holes in the legs 13 of the frame 12 in order to secure the frame 12 to the channel members 7.

As indicated above, the seat 8 and back 9 are hinged together by means of hinges 10. The latter may be of a kind which permit of the turning of the back 9 up to a certain predetermined angle on one hand or to collapse down to the seat 8 on the other hand.

The rear end of each of the frame legs 13 carries a top member 14 disposed on each side of the chair 2. The two top members 14 are designed to form an extension of the table top 5 and the upper face of the latter is flush with that of the top members 14. The top members 14 may, preferably, be connected integrally or by a separate member 15.

In case the connecting member 15 is provided, it may be used as abutment for the back 9 of the chair 2. While the member 15 may be disposed at the remote end of the member 14, it may be

arranged adjacent the table top, thus forming an extension of the latter.

Although the frame legs 13, when extending through the channel members 7, form sufficient support for the chair 2, it is preferred to provide an additional leg support which comprises a preferably tubular U-shaped leg frame 16 having a base 17, adapted to contact the ground or floor, and two vertically disposed leg members 18 which extend into horizontally turned end members 19. The latter are hinged by pivots 20 to the rear ends of the frame legs 13. At least one spring bolt 20' disposed on the horizontal end member 19 and extending into a corresponding hole 21 in the frame legs 13 retains the leg support in operative position (Fig. 3).

A footrest 22 may be hinged by special hinges 23 to the front end of the seat 8. A slotted bar 24 is secured to the bottom face of the seat 8 and a link 25 is disposed between the bottom face of the seat 8 and that of the footrest 22. One end of the link 25 is pivoted to the bottom face of the footrest, while its other end carries a pin 26 which slides in the slot of the bar 24. A rest (not shown) provided in the front end of the slotted bar 24 retains the footrest 22 in operative position and permits also the turning of the footrest 22 towards the seat 8 into inoperative position.

As shown in Fig. 5, the attachment member 3 together with the chair 2 may be completely collapsed by turning the footrest 22 towards the seat 8 and upon withdrawal of the spring bolt 20' by turning the leg frame 16 towards the frame 12.

Referring now to Figs. 6-10, the second embodiment of the baby tender is substantially identical with the above described first embodiment. The second embodiment comprises again a table 1', a chair 2' and an attachment member 3'. The table legs are formed again, preferably, of U-shaped members 4' which support the table top 5' and horizontally disposed cross-bars 6' connect the corresponding legs of the U-shaped members 4'. U-shaped channel members 7' are disposed under the table 1' in similar manner as disclosed with the first embodiment.

It is a particular feature of the second embodiment that the chair 2' is releasably connected to the attachment member 3' and thus a table and chair set as disclosed in my Patent No. 2,516,744 which may be transformed into a high chair, may also be used for the present baby tender. While the first embodiment of the baby tender required an attachment member with a specially designed chair, the second embodiment requires merely an attachment member in addition to a table and chair set, as disclosed in my Patent No. 2,516,744. Although any suitable chair may be used for the present purpose, it is preferred to use a chair which lends itself to form also a high chair in combination with the table 1'. Thus the chair may comprise a seat 8' and a back 9' which are supported by two preferably tubular members 10', the horizontal upper portions 11' of which serve as arm supports, while the horizontally extending bottom portions serve as bars to be received by the said channel members 7' when transformed into a high chair.

When used for a baby tender, the chair 2' stands on the ground floor next to the table 1'. The attachment member 3' comprises, as in the first embodiment, a U-shaped preferably tubular frame 12' the legs 13' of which are adapted to be received by the channel members 7' of the table 1'. The rear end of each of the frame legs 75

13' carries a top member 14' disposed on each side of the chair 2'. The two top members 14' are, as in the previous embodiment, designed to form an extension of the table 1' and are flush with the top of the table 1'. The top members 14' may be connected by a separate or integral member, as shown in the first embodiment, but are, preferably left open (Fig. 7) in order to permit of easy insertion and removal respectively, of the chair 2'. The first embodiment of the chair retaining means comprises a latch 15 which is pivoted to the rear end face of each of the top members 14'. The latches may be turned into the horizontal chair locking or operative position (Fig. 10) or into the inoperative position (Fig. 9) which permits of easy removal of the chair 2'. An angle 16' at one end of the latch 15' operates as abutment for the latch 15' when turned into operative position.

Thus the chair 2' can easily be inserted between the top members 14', as shown in Fig. 6 and the latch members 15' engage the rear face of the back of the chair 2'.

Referring now to Figs. 11 to 15, the second embodiment of the chair retaining means comprises a locking member 15' which releasably secures the attachment member 3' not only to the table 1' but also to the chair 2'. Though any suitable locking member may be provided for the chair 2', the locking device as commonly used for high-chair trays may be used for the present purpose. In this case the horizontal arm support portions 11' are equipped with longitudinally disposed metal plates 16' which have at least one perforation 17' adapted to receive a pin 18' of a spring biased pivoted lever 19' to lock the chair 2' in position. The attachment member 3' comprises the U-shaped tubular frame 12' which carries the top members 14'. A spacing member 20' is secured to each of the top members 14' and the remote end thereof carries a preferably U-shaped channel member 21' which is adapted to receive the perforated metal plate 16'. The lever 19' is of L cross-section and pivoted to the base of the channel member 21'. The latter has a recess 22' which receives the pin 18' or turned-up end of the lever 19'. A spring 23' disposed between the inner face of the lever 19' and the outer face of a branch of the channel member 21' tends to keep the lever 19' in locking position, as clearly shown in Fig. 13 which also demonstrates the metal plate 16' inserted in the channel member 21' and the turned-up end 18' or pin of the lever 19' received by the recess 22' of the channel member 21' and by the perforation 17' of the metal plate 16'.

Referring now to Fig. 16, the third embodiment of the chair retaining means comprises a rod 15' preferably of metal, which is disposed in vertical direction and extends through a bore 16' of the arm support portion 11' of the chair 2'. The upper end of the rod 15' is bent over 90° to extend in horizontal direction through a clamping member 17' which is screwed to the bottom face of the top member 14' of the attachment member 3'. The horizontally disposed portion of the rod 15' terminates into an end portion bent 90° to permit of free turning in the clamping member 17' without removal therefrom. When the two rods 15' are inserted into the bores 16' of the arm supports 11' of the chair 2' and then the frame 12' inserted into the channel members of the table, the chair 2' is releasably secured to the table.

While I have disclosed several embodiments of the present invention, it is to be understood, that these embodiments are given by example only and not in a limiting sense, the scope of the present invention being determined by the objects and the claims.

I claim:

1. In an article of manufacture for use by children, the combination of a table having two substantially horizontally disposed guide members with an attachment member including a pair of substantially horizontally disposed portions removably received in said guide members, at least one of said horizontally disposed portions carrying table top extension means, a chair having a seat being disposed between the said horizontally disposed portions, and means for retaining the said chair adjacent the said table.

2. In an article of manufacture for use by children, the combination of a table having two substantially horizontally disposed guide members, with an attachment member including a pair of substantially horizontally disposed portions removably received in said guide members, each of said horizontally disposed portions carrying table top extension means flush with the top of the said table, said table top extension means being in parallel arrangement, a chair having a seat being disposed between the said horizontally disposed portions and means for retaining the said chair between the said horizontally disposed portions adjacent the said table.

3. In an article of manufacture for use by children, the combination of a table having two substantially horizontally disposed channel members, with an attachment member including a pair of substantially horizontally disposed portions removably received in said channel members, at least one of said horizontally disposed portions carrying table top extension means a chair having a seat being disposed between the said horizontally disposed portions, and means for retaining the said chair adjacent the said table.

4. In an article of manufacture for use by children, the combination of a table having two substantially horizontally disposed channel members, with an attachment member including a pair of substantially horizontally disposed portions removably received in said channel members, each of said horizontally disposed portions carrying table top extension means flush with the top of the said table, said table top extension means being in parallel arrangement, a chair having a seat being disposed between the said horizontally disposed portions and means for retaining the said chair between the said horizontally disposed portions adjacent the said table.

5. In an article of manufacture for use by children, the combination of a table having two substantially horizontally disposed guide members below the top of said table, with an attachment member including a pair of substantially horizontally disposed portions removably received in said guide members, at least one of said horizontally disposed portions carrying table top extension means a chair having a seat being disposed between the said horizontally disposed portions and means for retaining the said chair adjacent the said table.

6. In an article of manufacture for use by children, the combination of a table having two substantially horizontally disposed guide mem-

bers below the top of said table, with an attachment member including a pair of substantially horizontally disposed portions removably received in said guide members, each of said horizontally disposed portions carrying table top extension means flush with the top of the said table, said table top extension means being in parallel arrangement, a chair having a seat being disposed between the said horizontally disposed portions and means for retaining the said chair between the said horizontally disposed portions adjacent the said table.

7. The article of manufacture, as set forth in claim 2, which includes a connecting member disposed between the said table extension means.

8. The article of manufacture, as set forth in claim 1, which includes means for pivotally connecting the said chair to the said attachment member.

9. The article of manufacture, as set forth in claim 1, which includes link members pivotally connecting the seat of the said chair to the said horizontally disposed portions of the attachment member.

10. The article of manufacture, as set forth in claim 9, which includes a leg support comprising a U-shaped frame, the base resting on the ground and the legs of the said frame being pivotally connected to the said horizontally disposed portions, and means for releasably retaining the said U-shaped frame in substantially vertical operative position.

11. The article of manufacture, as set forth in claim 1, in which said chair rests on the ground and said retaining means for the said chair comprises releasable locking means engaging the said chair to prevent the involuntary movement of the chair.

12. The article of manufacture, as set forth in claim 11, in which said chair has arm supports and said locking means includes two lock elements, one of the elements being secured to said arm support and the other complementary element being secured to the attachment member.

13. The article of manufacture as set forth in claim 12 in which one of said locking elements includes a spring biased lever to be received by a corresponding opening of the other lock element.

14. The article of manufacture, as set forth in claim 1, in which said chair rests on the ground, and latch means pivoted to the end faces of the said top members to be turned into horizontal position engaging the back of the chair and, thereby, retaining the chair in operative position and to be turned into vertical position in order to release the chair from its position adjacent the said table.

15. The article of manufacture, as set forth in claim 1, in which said chair has an arm support and which includes a substantially vertically disposed rod member secured to said top member and extending downwardly therefrom, said arm support having a substantially vertically disposed bore receiving the said rod member, so that upon inserting the horizontally disposed portion of the attachment member into the corresponding guide member of the table, the chair is releasably secured to the table.

16. In an article of manufacture for use by children, the combination of a table having two substantially horizontally disposed channel mem-

bers below the table top, with an attachment member including a pair of substantially horizontally disposed portions removably received in said channel members, at least one of said horizontally disposed portions carrying table extension means, a chair having a seat being disposed between the said horizontally disposed portions and means for retaining the said chair adjacent the said table.

LOUIS GOTTFRIED.
